METHOD OF MAKING SPARK PLUGS

Edward D. Rollert, Flint, Mich., assignor to General Motors Corporation, Detroit, Mich., a corporation of Delaware

Application April 22, 1942, Serial No. 439,992

2 Claims. (Cl. 29—25.12)

This invention relates to a method of securing a grounded electrode to the shell casing of a spark plug.

Engineers in the spark plug industry have always been faced with a considerable problem in the design of the grounded electrode. It is important that this electrode be well secured to the shell casing to provide a maximum of mechanical strength and it is also important that good contact between this electrode and the casing be maintained so that the electrical and heat conductivity from the grounded electrode to the shell casing be maintained at a high value. Spark plug electrodes are exposed to extremely high temperatures in the normal use of the plug. The temperatures have recently been increased due to rising cylinder pressures. The heat resulting from these high temperatures must be dissipated by flowing to the shell casing, whence it flows to the engine cylinder and is dissipated in the engine cooling system. It is therefore important that the heat conductivity of the joint between the electrode and the shell casing be maintained at a high level. This is particularly true in the production of modern aircraft where high cylinder pressures are utilized to lower the weight per horse power ratio.

It is the object of this invention to provide a spark plug having a shell casing to which the grounded electrode is welded for a maximum of mechanical strength, and high electrical and high heat conductivity. It is a further object of the invention to provide a method of welding which does not result in the formation of a "flash" on the inside of the shell casing, where access to the flash for its removal would be extremely difficult. This method provides a flash trap into which the molten metal of the flash may flow, preventing inward radial flow of the flash which would have to be removed to prevent interference with or impairment of the efficiency of the plug.

Figure 1 of the drawing shows a view in elevation, with parts broken away and in section, of a spark plug shell casing and the grounded electrode before the two have been welded together.

Figure 2 is a view of the construction of Figure 1 after the weld has been completed.

Figures 3, 4 and 5 show a simplification of the type of weld shown in Figure 2. Figure 3 is a view of the assembly before welding, Figure 4 is a view after the weld has been completed, showing the external flash, and Figure 5 is a view of the completed shell casing and ground electrode with the external flash removed.

Figures 6 and 7 show another embodiment of the invention in which Figure 6 shows the parts before welding and Figure 7 shows them after welding.

Figures 8 and 9 show still another embodiment of the invention; Figure 8 shows the parts before welding, and Figure 9 shows them after welding.

Figure 10 is a bottom plan view of the shell casing shown in Figures 8 and 9.

In the embodiment shown in Figures 1 and 2, a shell casing 10 having a longitudinal opening or bore 12 therethrough is shown. The annular face 14 at the firing end of the shell casing is provided with a recess or counterbore 16. At the bottom of the counterbore an annular groove 18 is provided. This groove and bore 12 together define a ridge 20. Bore 12 is preferably relieved or rounded at its firing end as indicated at 21.

An electrode 22, which may be of a metal having a high-temperature corrosion resistance which is much better than the material of shell casing 10, is provided to seat in recess or counterbore 16. The bottom of the counterbore is preferably beveled as shown at 24 to provide line contact between shell casing 10 and electrode 22 as indicated at 26. Furthermore, so that there may be contact between the casing and the electrode at 26 and not between annular ridge 20 and electrode 22, annular ridge 20 is cut down a little so as not to make contact with the electrode. The weld will therefore begin to form at contact line 26. Metal from the electrode 22 will flow into groove 18, filling it as indicated at 28 of Figure 2. It should be pointed out here that the bevel 24 of the bottom of countersink 16 has been exaggerated for purposes of illustration. The angle which the bevel 24 makes with the horizontal may vary from 0° to 10°, preferably from 5° to 7°. The clearance between the end of annular ridge 20 and electrode 22 will preferably be of the order of magnitude of .002 to .007 inch.

As is indicated in Figure 2, the flash trap formed by annular groove 18 substantially eliminates the formation of a welding flash on the inside of bore 12 at the point where electrode 22 is joined to casing 10. It is also evident from a study of Figure 2 that the counterbore 16 presents numerous advantages. One of these is that there is substantially no external flash. There is therefore no need to eliminate fused metal along an outside diameter. More of this will be brought out subsequently. It is also evident from Figure 2 that this form has the advantage of providing the same material along the entire

length of casing 10 so that no difficulty is encountered in machining the exterior of the casing 10 so long as the depth does not exceed the thickness of the casing remaining at the end after the counterbore has been made. This advantage is of particular significance when it is considered that shell casings are conventionally threaded to engage the spark plug opening in the cylinder block.

Figure 3 is a simplification of Figure 1, in that casing 10' is not counterbored. Electrode 30 extends substantially across the entire end of casing 10'. Annular groove 18 is provided as before to furnish a flash trap to receive metal of electrode 30 as indicated at 32 of Figures 4 and 5. The annular face at the firing end of the shell casing may be tapered in this case also, in a manner similar to that of Figure 1, as indicated by 34 of Figure 3. Similarly, some clearance is preferably provided between the annular ridge 20 and electrode 30. As in Figures 1 and 2, opening 12 is relieved or rounded at the firing end, as indicated in Figure 3 by 21.

In connection with the embodiment shown in Figures 1 and 2 it was stated above that counterbore 16 had the advantage of eliminating any external flash. The simplified embodiment shown in Figures 3, 4, and 5 illustrates the external flash 36 formed in this embodiment of the invention and which is eliminated by the use of a counterbore as shown in Figures 1 and 2. Flash 36 may be removed by any well known machining process such as cutting, grinding, or the like. Also as stated in connection with Figures 1 and 2, the embodiment shown in Figures 3-5 has the disadvantage of presenting machining difficulties where the material of electrode 30 is extremely tough or difficult to machine as where a threading operation is performed after removal of the flash 36. However, flash 36 is nevertheless external and is readily accessible for the necessary machining process, but an internal flash would be far less accessible. It should be noted that the flash trap of Figures 3-5 prevents the formation of an internal flash in a manner similar to that of flash trap shown in Figures 1 and 2.

With some types of alloys, it may be found that there is considerable "sputtering" or "spitting" of the metal at the time of the weld. In the two embodiments of Figures 1 and 3, such spitting or sputtering would take place radially inward from contact line 26 right through the clearance between annular ridge 20 and electrode 22 or 30. This spitting or sputtering might result in the formation of some internal flash which in some cases might be sufficient to impair the efficiency of the finished plug. To make such spitting or sputtering impossible or unlikely, I have provided the embodiment shown in Figures 6-9. In the embodiment of Figure 6, the annular groove 18 is substantially as shown in the other embodiments. However, annular ridge 20 extends toward electrode 22' actually beyond contact line 26. In order, however, that preliminary contact be maintained at contact line 26 rather than between annular ridge 20 and electrode 22', electrode 22' has been recessed as indicated at 38 of Figure 6. This recess may

take the form of a groove as shown in Figure 6 or merely a relieved flat as indicated at 40 of Figure 8. It will be seen, therefore, that annular ridge 20 will serve to dam or stop the flow

of any metal spitting radially inward from contact line 26, thus preventing the formation of any inner flash. The finished weld of these embodiments is shown in Figures 7 and 9. It will be seen from a study of these figures that annular groove or flash trap 18 is substantially filled in by metal of the electrodes 22' and 30' as indicated at 28' and 32' respectively. The embodiment of the flash trap shown in Figures 6 and 7 has been indicated as applied in the case of an electrode welded in a counterbore, whereas the embodiment of Figures 8 and 9 has been shown as applied to an electrode welded directly across the firing end of the shell casing. It will, of course be understood to those skilled in the art that the flash trap embodiment of Figures 6 and 7 is not restricted to a counterbored shell casing and that the embodiment of the flash trap shown in Figures 8 and 9 may equally well be used where the shell casing is counterbored and the electrode is welded thereto in the counterbore.

It will, of course, be understood that the welding referred to above and in the following claims refers to forms of welding which result in the formation of "flash."

I claim:

1. In spark plug manufacture, forming a metal shell casing having a longitudinal opening and having at one end an annular face lying generally in a plane, forming a groove in said annular face, providing a ridge inwardly of the groove and projecting beyond the plane of the annular face and welding an electrode to the grooved face of the shell casing, said electrode having an outer peripheral portion of not greater dimensions than the external periphery of the annular face and a relieved portion receiving said ridge and spaced therefrom, said welding operation causing metal from the electrode to fill in the groove in the annular face and to be trapped therein, and said ridge and relieved portion cooperating during the welding operation to prevent inward flow of flash.

2. In spark plug manufacture, forming a metal shell casing having a longitudinal opening therethrough and having at one end an annular face lying generally in a plane, relieving the inner edge of the annular face, forming an annular groove in the annular face between the relieved inner edge of the annular face and the outer edge thereof, providing a ridge inwardly of the groove and projecting beyond the plane of the annular face and welding an electrode to the grooved face of the shell casing, said electrode having an outer peripheral portion of not greater dimensions than the external periphery of the annular face and a relieved portion receiving said ridge and spaced therefrom, said welding operation causing metal from the electrode to fill in the groove in the annular face and to be trapped therein, and said ridge and the relieved portion in the electrode presenting a tortuous path whereby inward flow of flash is restricted.

EDWARD D. ROLLERT.
